United States Patent Office

Des. 183,868
Patented Nov. 4, 1958

183,868

CASKET

Walter E. Wallace, Richmond, Ind., assignor to Wallace Metal Products, Inc., Richmond, Ind., a corporation of Indiana

Application December 2, 1957, Serial No. 48,738

Term of patent 14 years

(Cl. D19—1)

Fig. 1 is a plan view of the casket, showing my new design;

Fig. 2 is a side elevation thereof; and

Fig. 3 is a fragmental end elevation of the casket on an enlarged scale.

I claim:

The ornamental design for a casket, as shown.
